Follow the Clues...Messages from the Angels

We are all children walking on the golden pathway to the sunlight. This is an educational game for all to teach and share the true meaning of life. As you walk on the golden pathway you will experience positive actions and deeds. When we switch our thinking, actions and deeds to that of fear and negativity our energy has the potential to slip and slide backwards. We tend to remain there until we learn our lessons.

The game board "Follow the Clues...Messages from the Angels" is done in circles. There is no beginning and no end. For each one to reach our highest level we must go to the next dimension. We continue on our journey till we reach complete joy, inner peace and bliss. There are no winners or losers in the game. When the first player reaches his goal, he is obligated to go back and help another player on the board with his support and encouragement to reach his or her goal.

The game maybe played by 2-6 players. Recommended for children age 10 and up.

Step 1

The game begins as you walk the pathway to Inner Peace and step onto the space "Set the Intention for your Life's Plan." Before you move the spinner, you are to set your intention for your life and then begin on the journey with spinning this wheel. The object of the game is to reach the Sunlight.

Step 2

Spin the wheel and move your pawn to the space indicated. If you land on an Angel space you must pick an angel card from the deck and read it out loud. Each card will identify a specific angel and its power and give you clues that will help you on your pathway through life. All of the 27 angels within the deck of cards have a unique mission designated by the Mighty Universal Source. If you land on an action word you will follow the instructions in the "Words Description and Rules" pamphlet. Remember to always ask the angel to help you on your journey. They are always here to guide you. However, you must ask for their assistance.

PLEASE NOTE: It is your responsibility to remember the function of these angels, follow the clues and receipt them when needed throughout the game.

Step 3

If you land on the ladder, you are granted the blessing of climbing to the next level. If you land on a slide, you must go down the slide and begin to move again from the point where you landed. You can however, choose yourself if you can make a positive affirmation in the space that represents this opportunity. If you cannot recall the angel by name, you can get the help from one of your teammates. Life is a journey where we are constantly looking for help, along the way. If, however, we choose the ladder, we must climb the stairs, thus you must stay at the space you slid down to and continue from this point. Throughout this game as throughout your life, it will benefit you to remember to ask for help in having the courage and strength to continue on your pathway.

Step 4

The game is over when all players reach the sunlight. If one player is successful in reaching the sunlight, he or she must become the helper for another on the board (you chose who you wish to help). Through positive reinforcement and encouragement, all the players will eventually reach the sunlight. To step into the sunlight, the player must land on the space number on the spinner. The first player to touch the sunlight wins and recite the power that is on the sunlight card.

Temper these emotions with laughter and humor. Anger and rage are trapped emotions released in an unexpected way and time. Learn to acknowledge these emotions and bless them with love and gratitude. Once you acknowledge and address them, you will have the opportunity of releasing their negative energy and be filled with gratitude and love...the most powerful energy in the Universe. The heavenly angels sing in great unison when you choose divine mercy and compassion. Extremes of any kind are unhealthy. Ask Remiel for help.

A closed heart destroys that which it tries to awaken...open your heart to receive the blessings and gifts that the Universal Source has marked for you. Guilt, feelings of unworthiness, shame all feed into the trap of victimhood. Release these emotions and be filled with greater self-worth, self-assuredness, self-resolve knowing that you have all that you need within you to make it right. Possibly it was Amitiel sending you signals of confirmation through your positive feelings and intense vibrational energies. When your heart feels open and good, accept this as a positive affirmation that what you are experiencing is good. If you get a check in your spirit, a gnawing feeling that causes you to question the vibration you are experiencing, then know that this is not for your highest and best good. As you accept and honor your true feelings, light and love will shine through and you will experience great joy and resolve.

Allow yourself to understand why you needed to go through the experience. Work on healing the pain by going beneath it and sending the hurt, the pain, the discomfort your love. By doing this we will start to create a new world order where we accept and acknowledge all creatures as beautiful and precious. To accomplish this mission, Iofiel is helping us look at ourselves first.
